UNITED STATES PATENT OFFICE.

EDWARD B. SHIELDS, OF TACOMA, WASHINGTON, ASSIGNEE, BY DIRECT AND MESNE ASSIGNMENTS, TO TURTLE-BACK LOG BUNK & CAR STAKE COMPANY, A CORPORATION.

CAR-STAKE.

1,072,516.

Specification of Letters Patent.

Patented Sept. 9, 1913.

Application filed March 25, 1912. Serial No. 686,006.

To all whom it may concern:

Be it known that I, EDWARD B. SHIELDS, a citizen of the United States, residing at Tacoma, in the county of Pierce and State 5 of Washington, have invented a new and useful Car-Stake, of which the following is a specification.

This invention relates to car stakes and especially to such stakes as are for use on 10 cars for hauling logs.

The objects of my invention are to provide a stake which will be permanently mounted on the car; which can be easily released from its operative position; which 15 can be easily and quickly placed into operative position; which can be operated from the opposite side of the car; in which a series of stakes on a side may be simultaneously released or any one of them separately released; and in which the released stake is 20 withdrawn into the supporting bunk and does not protrude therefrom to catch in any structure forming part of the log-dump or in any way interfere with the free operation 25 of the train.

Further objects are to improve the form of the bunk on which the logs rest; and to provide a stake and bunk which may be used on a logging truck.

I attain these and other objects by the devices, mechanisms, and arrangements illustrated in the accompanying drawings, in which—

Figure 1 is a vertical cross-section of a 35 car frame showing my improved stakes in elevation, both stakes being in operative position; Fig. 2 is a vertical section across the car showing the bunk and stakes in section and showing one stake released; Fig. 3 is a 40 side elevation of a portion of the car showing one stake in operative position and the other stake released; Fig. 4 is a vertical cross-section of two bunks, illustrating especially the device for tripping both stakes on 45 a side simultaneously; Fig. 5 is an elevation illustrating the means for actuating said tripping device; Fig. 6 is a view showing the position of a portion of said tripping device after the stakes have been released; 50 Fig. 7 is a plan of a bunk and pair of stakes mounted thereon; Fig. 8 is a perspective view of the stake and the end of a bunk, illustrating especially the means for tripping one stake alone; Fig. 8^a is a perspective view of the end of one of the controlling 55 bars; Fig. 9 is an elevation showing a logging truck equipped with my improved stakes and bunk; Fig. 10 is a vertical section of the logging truck bunk; and Fig. 11 60 is a front elevation thereof.

Similar numerals of reference refer to similar parts throughout the several views. 65 The car deck 1 is supported on suitable side sills 2 and intermediate sills 3 in the usual manner. At any number of points in the car deck, but preferably in two suitable points, the deck 1 is removed entirely across the car and the bunks 4 are secured in place across the car on the said sills 2 and 3. 70 Each bunk 4 is made of metal and is hollow being shaped like an inverted U, having a curved or arched top on which the logs rest and having no bottom, and the stakes 5 are mounted in each end of the bunk and their controlling bars extend across the car 75 within the bunk. Each bunk 4 has a slot or socket with vertical parallel walls at each end, in which the stakes 5 are mounted and operate. Each stake 5 is made of metal and is formed with a part adapted to extend 80 vertically up from the end of the bunk to form the stake proper, and with a radius part 7 (Fig. 2) extending substantially at right angles to the said vertical part, and with a curved part 8, being substantially an 85 arc of a circle in continuation of the vertical part. The stake is pivoted to the bunk 4 by a pin 9 which passes through the bunk near the top of the arch and through the end of the radius part 7, said pivot pin 9 being 90 the center of the circle of the part 8. The part 8 is forked at its end to receive the bar 10 which extends therefrom across the car, within the bunk, at a slight angle so as to pass to one side of the stake 5 at the other 95 end of the bunk. The bunk 4 has a hole 11 in its end wall, to one side of the stake slot, at each end, through which hole the end of the bar 10 passes, and said bar has a notch 12 in its lower edge near its end and a second notch 32 similarly positioned but farther from the end thereof, both of said notches being adapted to fit over the wall 100 forming the lower edge of the hole whereby the bar is held in either one of two positions. 105 These positions are such that when the stake 5 is in its vertical or operative position the bar 10 just extends a short distance through

the hole 11 and the outermost notch 12 is in engagement with the wall of the bunk through which the hole has been made, (right-hand end of Fig. 2) while if the stake 5 is in its withdrawn position the bar 10 extends farther through the hole and the other notch 32 is in engagement with the said part (left-hand end of Fig. 2). The positions, sizes, and proportions of the parts are such that when the stake is released the vertical part thereof is withdrawn into a horizontal position and does not extend substantially beyond the end of the bunk.

It is evident that if a stake is to be released all that is necessary to do is to raise the end of its bar so as to remove the notch 12 out of contact with the wall and the stake will immediately turn on its pivot pin 9 and drop, forcing the bar 10 farther out of the hole 11 until the inner notch 32 thereon catches on the wall and holds the stake in the withdrawn position. The end of the bar 10 may be raised to release the stake by a hand bar 13 (Fig. 8) which rests on a lug 14 formed on the end of the bunk 4 and which engages under the said bar 10. A releasing mechanism is also provided whereby all the stakes on one side of the car may be simultaneously released (Figs. 4, 5 and 6). This consists of a lever 15 pivoted to the bunk adjacent to each bar, at a point between the side sill 2 and the adjacent intermediate sill 3, in such position and of such shape that a portion thereof will engage under the lower side of the bar to raise the bar in the hole when the said lever 15 is actuated. All of these levers 15 are attached together by means of connecting rods 16 so that they all operate together. One of the levers 15 is provided with an extension 17 on which a vertical link 18 is mounted, said link extending through a suitable hole in the deck 1 or in a flange of the bunk 4 (Fig. 6). This link 18 has a hole 29 near its end in which the end of a bar 19 (Fig. 5) can be placed, said bar resting and fulcruming on a lug 20 formed near the end of the bunk. By pressing down on the outer end of the bar 19, its inner end is raised thus raising the extension 17 and all of the levers 15 and simultaneously allowing all of the stakes 5 on the other side of the car to be released.

Referring now to Figs. 9, 10 and 11: I have here shown the bunk 24 provided with a vertical central flange 26, and the stakes 25 provided with similar flanges 28 extending inward therefrom all said flanges 26 and 28 being adapted to sink into the bark of the logs to firmly attach the logs to the bunk and prevent any endwise motion thereof thereon and thus to fasten the logging trucks at each end of the logs together. The bunks 24 are provided with central king-pins 27 engaging the cross-beam of the truck in the usual manner. The other parts

of this logging truck bunk and stakes are similar to those already described.

Having described my invention, what I claim is:

1. In a device of the class described, the combination of a bunk extending across the car and having an arched top adapted to support the logs, and an open bottom whereby no dirt is retained therein; a stake adapted to extend above the bunk when in its operative position and to be withdrawn into the bunk when in its inoperative position; an arm extending inward from and forming part of said stake and pivoted to the bunk adjacent the upper surface thereof; and a bar pivotally secured to the lower end of the stake and passing therefrom across the car within the bunk and releasably engaging the end wall of the bunk whereby the bar is held from movement and the stake is maintained in operative position. 70 75 80 85

2. In a device of the class described, the combination of a bunk extending across the car; stake guides formed on the end of said bunk; a stake lying between said guides and adapted to extend above the bunk when in its operative position and to be withdrawn into the bunk when in its inoperative position; an arm extending inward from and forming part of said stake and pivoted to the upper part of the bunk adjacent said stake guides; and a bar pivotally secured to the lower end of the stake and passing therefrom across the car and releasably held from movement whereby the stake is maintained 90 95 100 in operative position.

3. In a device of the class described, the combination of a bunk mounted across the car, and formed of a substantially inverted U-shaped hollow body terminating in stake 105 guides at its ends; of a stake, formed of an arm the free end of which is pivoted to the bunk adjacent the upper surface thereof, a vertical part extending at substantially right angles to said arm and adapted to extend 110 above the bunk to form the stake when in operative position and to be withdrawn into the bunk when in its inoperative position, and a curved part in continuation of said vertical part and extending rearward under 115 the arm; and a bar pivotally secured to the end of said curved part and passing therefrom across the car within the bunk and passing out from the end of said bunk and having a notch in its under surface adapted 120 to engage the end wall of the bunk whereby the bar is held from movement and said stake is maintained in position.

4. In a device of the class described, the combination of a hollow bunk mounted 125 across the car; of a stake pivoted to one end of said bunk and extending upward therefrom, when in its operative position, but withdrawn into said bunk when in its inoperative position; a bar within said bunk 130

and engaging at one end the lower end of said stake and extending to the other end of said bunk; and means for holding the other end of said bar whereby said stake is held in operative or inoperative positions.

5 5. In a device of the class described, the combination of a hollow bunk mounted across the car; of a stake pivoted to one end of said bunk and extending upward therefrom when in its operative position, but withdrawn into said bunk when in its inoperative position; and a bar within said bunk and engaging at one end the lower end of said stake and extending to the other end of 10 said bunk, and having notches in the lower edge at its other end, said notches being adapted to engage the outer wall of the bunk whereby said stake is held in operative or inoperative positions.

15 6. In a device of the class described, the combination of a hollow bunk mounted across the car; of a stake pivoted to one end of said bunk and extending upward therefrom when in its operative position, but withdrawn into said bunk when in its inoperative position; a bar within said bunk and engaging at one end the lower end of said stake and extending to the other end of said bunk, and having notches in the lower edge at its other end, said notches being adapted to engage the outer wall of the bunk whereby said stake is held in operative or 20 inoperative positions; and means for raising said bar to disconnect said notch

from the holding wall whereby said stake is released from its held position.

7. In a device of the class described, the combination of a hollow bunk mounted across the car; of a stake pivoted to one end of said bunk and extending upward therefrom when in its operative position, but withdrawn into said bunk when in its inoperative position; a bar within said bunk and engaging at one end the lower end of said stake and extending to the other end of 40 said bunk, and having notches in the lower edge at its other end, said notches being adapted to engage the outer wall of the bunk whereby said stake is held in operative or inoperative positions; and a lever engaging 45 said bunk and the under side of said bar whereby said bar is raised to disconnect the notch from the holding wall whereby said stake is released from its held position.

8. In a device of the class described, the combination of a bunk mounted across the car; a stake pivoted to one end of said bunk and extending upward therefrom when in its operative position; and a bar secured to said stake below the pivot thereof and extending across the car and having its free end abutting against the outer wall of the bunk whereby said stake is held in operative position.
